UNITED STATES PATENT OFFICE

2,533,037

APPARATUS FOR WINDING YARNS ON CARDS

Mario Nava, Macclesfield, England

Application December 19, 1947, Serial No. 792,770
In Great Britain July 21, 1944Section 1, Public Law 690, August 8, 1946
Patent expires July 21, 1964

1 Claim. (Cl. 242—50)

1

This invention has reference to apparatus for winding yarns on cards and has for its object to provide a simple and convenient means whereby predetermined lengths of yarn, such as silk, artificial silk, wool and other yarns, which are required in small quantities can be wound.

Apparatus for winding predetermined lengths of yarn on cards according to this invention comprises a plate, adapted to carry a card, mounted on a shaft rotated through gearing by the operator, the gearing being rotated by a handle, the apparatus having a lever co-operating with a counting wheel to indicate when the predetermined number of turns made by the handle and hence the number of windings on the card is complete, the yarn being drawn from cheeses, pirns or the like and led through eyes and round drag rods to exert a tension on the yarn.

The invention is more particularly set forth with reference to the accompanying drawings wherein—

Fig. 1 is an end elevation of an apparatus made according to the invention;

Fig. 2 is a plan; and

Fig. 3 is a front elevation partly in section.

The apparatus as shown in the drawings has a base 4 on which the cheeses, pirns or other packages 5 for the yarn can be stood when the apparatus is in use. These packages 5 are conveniently placed on pins 6 to keep them in place while the yarn is being drawn off and to reduce the width of the base 4, the yarn packages may be staggered, or arranged in rows from front to back. Above the yarn packages 5 are cross members 7 on supports 8 the cross members 7 having eyes 9 through which the yarn is led till it passes through eyes 10 on a cross member 11 vertically adjustable in supports 12 and secured by nuts and bolts 13.

In front the apparatus which comprises the actual winding gear has two end plates 14 and 15 at one end with a plate 16 at the other end, and in the plates 15 and 16 are holes 17 in which are mounted drag rods 18 at the back and drag rods 19 at the front, under which the yarn 20 is passed, the rods can be mounted in any pair of holes 17 opposite to one another in the plates 15 and 16 and by this means tension or drag can be applied to the yarn and to this end the rods may be covered with felt or the like.

Above the rod 19 at the front is a further rod 21 having on its eyes 22 through which the yarn passes to the top edge of a card 23 on which the yarn is wound. This card 23 is held on to a metal plate 24 by a spring clip 25 and the plate 25

itself is clamped firmly at its other end in a clamp 26, provided with a slot into which fits the other end of the card 23 so that it is held flat and firm.

- 5 The clamp 26 is mounted on, and rotates with, a shaft 27 mounted in bearings in the plates 14 and 15 and having a pinion 28 on it engaged and driven by spur wheel 29 on a shaft 30 and compounded with a pinion 31 on the same shaft 30 which pinion 31 is driven by a spur wheel 32 on a shaft 33 rotated by a handle 34. The spur wheel 32 has on the inside—see Fig. 2—a counting wheel in the form of a flange 35 with a gap 36 and mounted pivotally between the plates 14 and 15 is a finger lever 37 urged down by a spring 38 and provided with a projection 39 which will engage the gap 36 in the flange 35 and hold the whole mechanism against rotation when so doing.
- 10 20 If, however, the finger lever 37 be pressed down, thus lifting the projection 39 out of the gap, as when starting the machine, the handle can be turned thus setting the whole gearing into motion, but stopping it again if the finger lever has been released, as and when the gap 36 comes round again under the projection 39. In this way and by allowing the end 39 of the lever to rest on the flange 35, the number of turns of 15 30 35 yarn on the card 23 for each rotation of the flange 35 is automatically regulated or “counted” and the whole apparatus is held still while the filled cards are detached, the yarn leading to the card being of course cut and while the new card is mounted in place and the free ends resulting 35 from the cutting are fixed to the new card.

As a rule when the apparatus is once set it will be used for long periods without alteration, but should it be desired to put a greater or shorter length of yarn on the card, this can be arranged 40 by removing the spur wheel 29 and pinion 28, the shaft on which they run being easily removable and putting in a new combination of gears to give for each rotation of the flange 35 the required number of turns to the shaft 27 and hence 45 the card 23. In this manner, for each rotation of the handle, there may be, according to the gearing employed, any number of rotations of the card, thus, if the card be say six inches wide, such rotation of the card will wind on one foot 50 of yarn and if the gearing be 10 to 1, one turn of the handle will wind on ten feet of yarn and in this manner, the length of yarn wound on the card is checked and counted.

In this way, by means on the counting wheel 55 the quantity of yarn wound round each section

of the card from each strand or end of yarn is regulated and controlled and all the operator has to do is to turn the handle until further movement is arrested by the counting wheel being held.

What I claim as my invention and desire to secure by Letters Patent is:

Apparatus for winding a plurality of equal lengths of thread side by side on a flat card comprising a base, vertical pins on said base for supporting packages of thread, vertical supports for guide and tension rods for the threads, adjustable guide and tension rods mounted in said vertical supports, guide eyes on said supports spaced apart at fixed distances, vertical supporting plates for the winding mechanism, said winding mechanism comprising a spindle, securing means at one end of said spindle for a rectangular plate, a rectangular plate mounted in the centre of one end on said securing means, the centre line of said plate being axially aligned with said spindle, said securing means having a slot for receiving one end of a flat card mounted on said plate, securing means at the other end for detachably holding said flat card on said plate, a pinion on said spindle, a gear wheel meshing with said pinion, a pinion compounded with said

gear wheel and both mounted on a detachable spindle, a gear wheel in mesh with said compounded pinion, manually operable means for rotating said last gear wheel, a flange on said gear wheel, said flange having a gap therein, and a spring actuated strip resting on said flange and engaging said gap at each rotation movement until manually released.

MARIO NAVA.
